CLAIM

The ornamental design for an audio device wall mount, as shown and described.

DESCRIPTION

FIG. 1 is a front elevation view of an audio device wall mount, according to a first embodiment;
FIG. 2 is a rear elevation view thereof;
FIG. 3 is top plan view thereof;
FIG. 4 is a bottom plan view thereof;
FIG. 5 is a first side view thereof;
FIG. 6 is a second side view thereof;
FIG. 7 is a perspective view thereof;
FIG. 8 is a front elevation view of an audio device wall mount, according to a second embodiment;
FIG. 9 is a rear elevation view thereof;
FIG. 10 is top plan view thereof;
FIG. 11 is a bottom plan view thereof;
FIG. 12 is a first side view thereof;
FIG. 13 is a second side view thereof; and,
FIG. 14 is a perspective view thereof.
The dashed broken lines in the figures show features of the audio device wall mount that form no part of the claimed design.
